His Attorney.

UNITED STATES PATENT OFFICE.

HUGO R. VOLAND, OF ST. LOUIS, MISSOURI.

SCENERY-BRACE.

1,220,032.

Specification of Letters Patent. Patented Mar. 20, 1917.

Application filed March 22, 1916. Serial No. 85,794.

To all whom it may concern:

Be it known that I, HUGO R. VOLAND, a citizen of the United States, and residing at St. Louis, in the State of Missouri, have 5 invented a certain new and useful Improvement in Scenery-Braces, of which the following is a specification.

This invention relates generally to stage settings, being directed more particularly to 10 scenery braces, such as are employed for bracing what are known as set pieces and holding such pieces in proper position.

In arranging stage settings the set pieces are usually held in place by means of braces 15 extending from the stage floor, it having been the practice, heretofore, to fix the lower ends of such braces to the floor by means of screws or the like. This practice is highly objectionable, not only because of the loss 20 of time involved and the difficulty of making what are known as "dark changes", but also because of the injury caused to the floors, carpets and other floor coverings. Furthermore, in the instance of modern 25 structures, wherein the stage floors are made of hard wood, concrete or the like, the employment of screws or other fasteners for holding the lower ends of the braces is, obviously impracticable.

30 This invention has among its objects, therefore, to overcome the above mentioned objections by providing a brace which will, without the use of floor engaging screws or fasteners, be thoroughly effective for bracing and holding the set pieces, and which will, therefore, operate without marring or otherwise injuring the floors or floor coverings.

Further objects of the invention are to 40 provide a simplified form of scenery brace which may be readily connected for use and which will, in action, permit ready shifting of the scenery and tilting or like adjustment of the set pieces, and wherein the 45 brace may be readily folded to unobstructing position, back of the piece of scenery, when not in use.

With the above and other objects in view, the invention comprises the novel features 50 of construction and combination of parts more fully hereinafter described.

In the accompanying drawing;

Figure 1 is a perspective view of a piece

of scenery equipped with braces embodying the invention;

55

Fig. 2 is a view on a larger scale, showing the brace in side elevation; and,

Fig. 3 is a detail view, in elevation of the lower portion of the brace.

Referring to the drawings, in which the brace is shown applied for use in connection with a piece of scenery 10, it will be seen that the improved brace comprises a main portion or bar 11, of suitable length, and of any appropriate material, provided, at its 60 upper end, with scenery engaging means, and, at its lower end, with a floor engaging cushion or pad 13, preferably composed of rubber, and of rounded or semi-spherical form, as shown, while the scenery engaging means is preferably in the form of a pin 12 and a latch finger 12' pivoted at its lower end to swing laterally to and from engaging position over the upper end of the pin 12.

Slidably mounted on the bar 11, for adjustment longitudinally thereof, is a bearing sleeve 14 having ears 15 in which is pivoted one end of a strut 16 provided, at its normally free end, with a scenery engaging hook 17, downward movement of the sleeve 70 14 on the brace bar being limited by a cross-pin or other suitable stop 18.

Mounted on the lower portion of the brace bar 11, for holding the lower end thereof in weighted engagement with the floor surface, is an elongated weight 19, preferably consisting of a length of bar metal, adapted to seat against the inner or lower side of said brace and to be adjustably held in place thereon by suitable U-shaped clips 20 pivotally connected with the weight and slidably fitted over the brace for frictional engagement therewith to hold the weight in adjusted positions, this weight being of such length that it will act to exert both a downward and an inward pull on the lower end of the brace, thereby holding the latter in proper engagement with the floor surface.

The piece of scenery 10 is provided with means, such as screw eyes 21, suitably 95 disposed for coöperation with the members 12 and 17 to hold the brace and strut in detachable engagement with the scenery.

In the operation of the device, the brace having been connected with the piece of 100 105 scenery by engaging the members 12 and 17

with the eyes 21, the lower padded end of the brace will, when the piece 10 is set up, rest upon the floor surface and be maintained in secure engagement therewith under the action of the weight 19, which, as before stated, extends along the brace in suitable position to exert a downward and inward pull, tending to draw the end of the brace toward the floor and also inward toward the 10 piece of scenery, it being noted that the pad 13 not only prevents marring of the floor surface, but, through frictional engagement therewith, supplements the action of the weight in holding the brace to its work. 15 Owing to the strut being connected for adjustment along the brace bar, the brace may be readily adjusted in setting the scenery and fixed in its adjusted positions, while the weight may be adjusted along the bar to 20 accord with such adjustments of the latter and to properly clear the floor, it being noted that during such adjustments of the weight, the clips 20 will slide freely along the brace but will frictionally hold the 25 weight against accidental movement. When the device is not in use it may be readily folded to an unobstructing position against the rear face of the piece of scenery, as shown by dotted lines in Fig. 1. In order to 30 so fold the brace, the bearing sleeve 14 is released and moved upward therealong, whereupon the brace may be swung laterally on the vertical pivot formed by members 12 and 17 and their bearing eyes 21. 35 The improved brace in its action obviates marring of the floor or floor coverings, permits of the scenery being freely shifted and set up, and provides for this shifting of the scenery being readily performed in the dark, 40 in making what are known as "dark changes." The device also provides for properly and securely bracing the scenery under conditions which render the use of stage screws or like fasteners impracticable. 45 In attaining these ends, the invention is not necessarily restricted to the structural details herein shown and described, inasmuch as various minor changes may be made therein without departing from the spirit or 50 scope of the invention.

Having thus described the invention, what is claimed is:

1. In a device of the class described, comprising a perpendicular piece of scenery, the

employment of a brace bar weighted adjacent its lower floor engaging end, and means for operatively connecting said brace with the piece of scenery, adapted to anchor and maintain the piece of scenery in perpendicular position. 55

2. A scenery brace comprising a brace-bar, a cushioning pad applied to the lower end thereof, a weight constructed and arranged for maintaining said end in secure frictional engagement with the floor surface, 60 and means for operatively connecting said brace with a piece of scenery. 65

3. A scenery brace comprising a brace-bar, a strut adjustably connected therewith, means for operatively connecting said brace 70 and strut with a piece of scenery, and a weight provided on said brace and constructed and arranged for maintaining the lower end thereof in secure engagement with the floor surface. 75

4. A scenery brace comprising a brace-bar, means for operatively connecting the same with a piece of scenery, a weight constructed and arranged for maintaining the lower end of said brace in secure frictional 80 engagement with the floor, and a strut operatively arranged between said brace and scenery. 85

5. A scenery brace comprising a brace-bar, a strut connected at one end for adjustment along said bar, means for operatively connecting said brace and strut with a piece of scenery, and a weight applied to said brace for maintaining the lower end thereof in secure engagement with the floor surface. 90

6. A device of the class described comprising a piece of scenery, a brace-bar, means for operatively connecting said brace with the piece of scenery, and a weight extending along said brace and operating to anchor the 95 scenery in set position and maintain the lower end of the brace in secure engagement with the floor surface.

7. A scenery brace comprising a brace-bar, a strut adjustably connected therewith, 100 means operatively connecting said brace and strut with a piece of scenery adapting the brace to be folded thereagainst, and means for holding the lower end of the brace in engagement with the floor surface. 105

In testimony whereof I affix my signature this 16th day of February, 1916.

HUGO R. VOLAND.
